H. M. FUNNELL

UNIVERSAL JOINT

Filed March 18, 1922

FIG. 1.

FIG. 2.

FIG. 3.

FIG. 4.

INVENTOR.
H. M. Funnell
BY
T. H. Luttmann
ATTORNEY.

UNITED STATES PATENT OFFICE.

HARRY M. FUNNELL, OF BLOOMFIELD, CONNECTICUT.

UNIVERSAL JOINT.

Application filed March 18, 1922. Serial No. 544,782.

To all whom it may concern:

Be it known that I, HARRY M. FUNNELL, a subject of the King of Great Britain, residing at Bloomfield, in the county of Hartford and State of Connecticut, have invented certain new and useful Improvements in Universal Joints, of which the following is a specification.

This invention relates to universal-joints, and while I have a number of important objects in view, the principal of them is the provision of effective means by which the moving parts of the joint can be adequately lubricated.

In the drawing accompanying and forming part of the present specification, I have shown in detail one of the several forms of embodiment of the invention, which to enable those skilled in the art, to practice the same will be set forth fully in the following description. I am not restricted to this disclosure. I may depart therefrom in a number of particulars within the scope of the invention defined by the claims following said description.

Referring to said drawing:

Fig. 1 is a side elevation, partly in longitudinal section, of a universal-joint involving the invention.

Fig. 2 is an elevation, partly in section, as viewed for instance from the left in Fig. 1.

Fig. 3 is a vertical section of a bushing and adjunctive means.

Fig. 4 is an inside view of the structure shown in Fig. 3.

Like characters refer to like parts throughout the several views.

The joint involves in its construction three main members, two of them generally being forked members and the third one usually consisting of a ring. In Figs. 1 and 2 I have shown two of these main members as 2 and 3, consisting as shown of stub shafts having forks at their forward ends. The branches of the forks are generally at right angles to each other and are provided with outwardly extending studs 4 fitted for turning motion in the third main member as the ring 5, the openings in the ring or main member 5 pivotally receiving the studs 4 which as will be understood are in coaxially aligned pairs at practically right angles to each other. This gives the necessary universal movement and is a brief description of a more or less familiar universal joint with which my lubricating means operates

as found in practice, in a highly satisfactory manner. It is clear that the lubricating means might be used equally effectively with other forms of universal joints.

In the present case, the lubricating mechanism involves casing means surrounding the joint and although the casing means is made up of segments, usually four, this is not a vital, yet it is an advantageous consideration.

The lubricant, ordinarily oil, is received in the construction shown by four segmental or arcuate casing members 6 which are arranged in annular order around the ring 5 so as to present almost a complete circle, the ends of the segmental or arcuate casing members being contiguous to each other. On their outer sides the segmental members 6 have filling openings 7 to receive removable plugs 8, the plugs being desirably threaded to engage threads on the walls of the respective opening 7 and being slotted to facilitate their insertion and removal when necessary.

The segments 6 have about centrally on their inner sides the tubes 9 which receive although they do not desirably directly engage the respective studs 4.

The respective tubes which it will be understood extend through openings spaced approximately ninety degrees apart in the ring 5, have at their inner ends outwardly extending flanges 10 which in turn are inwardly flanged as at 11. The flanges 10 bear on their outer sides against the ring 5. The studs 4 as will be noted extend entirely through the tubes 9 centrally thereof and at their outer ends are furnished with extensions 13 of somewhat reduced cross sectional extent. These extensions 13 also extend almost completely across the respective segmental member 6 about midway of the length thereof. Around the studs 4 and practically coextensive therewith, are bushings as 14 which engage at their inner ends the two yokes 2 and 3. The respective bushings 14 fit the tubes 9 and are provided with outwardly extending annular flanges 15 between which and the flanges 11, packing rings as 16 are situated. The outer sides of said packing rings fit the respective flanges 10, at their inner sides being solid against the yokes 2 and 3. The flanges 15 in turn have annular rabbets 17 on their inner sides.

The bushings 14 as shown have exteriorly thereof, the longitudinal external channels

or grooves 18 open at their ends and extending across the annular flanges 15. There may be as shown three of these channels and although their use is advantageous it 5 may not always be necessary to produce them in the bushings 14.

It will be assumed that the four casing members 6 are filled with oil and that the 10 joint is being rotated. The oil will be carried along the interior surfaces of the respective bushings 14 by capillary attraction and will flow outwardly into the channels 17 where its complete outward flow is checked by the packing rings 16. From the 15 rabbets or grooves 17, the oil, by centrifugal action will be thrown outwardly along the channels or passages 18 and will be returned back into the casing members 6 which obviously act as reservoirs for the oil. Clearly 20 there is no waste of the oil and all parts are adequately uniformly, and properly lubricated.

The joint heretofore described, is operated on principles not heretofore used with 25 other oil lubricated joints. These principles are the fact that the oil reservoir is put exteriorly to the point at which leakage can occur while the joint is in action. This results in centrifugal force which tends to 30 drain the oil away from the bearings, as distinguished from prior attempts. The lubrication of this joint is secured owing to the fact that no propeller shaft in an automobile rotates at a constant speed, due to 35 obstructions in the road such as caused by corners, pedestrians and like conditions which cause the irregular driving.

Let it be assumed that the joint covered 40 hereby is rotating at a constant speed. In this event the oil in the reservoirs will tend to travel in the same direction as the reservoirs but a little slower than the reservoirs due to friction. As each reservoir is complete in itself, the oil tends to fill up the back 45 portion of each reservoir. When the speed of the joint is reduced, the oil due to its momentum, is in fact, travelling faster than its reservoir which causes it to be thrown to the opposite end of its reservoir. 50 In doing this, it has to splash the projection of the journal provided for this purpose.

From the statements made, it will be 55 evident that the bearing covered hereby is radically different from prior patents, as briefly, centrifugal force is used to drain the oil into a sealed receptacle away from the bearing surfaces and an intermittent splash system is utilized to lubricate them, whereas, in prior forms, centrifugal force is used to make the oil flood the bearings and the splash feature is omitted.

What I claim is:

1. A universal joint comprising two forked members at approximately right angles to

each other and the branches of which have external studs, a ring surrounding the forks and in which the studs are pivotally received to connect the forked members for universal movement, a series of hollow segmental lubricant receiving casing members surrounding the ring and the ends of which are contiguous, the casing member having openings and the studs having extensions extended into the respective casing members by way 70 of the openings.

2. A universal joint comprising two forked members at approximately right angles to each other and the branches of which have external studs, a ring surrounding the forks 80 and in which the studs are pivotally received to connect the forked members for universal movement, a series of hollow segmental lubricant receiving casing members surrounding the ring and the ends of which are contiguous, the casing member having openings and the studs having extensions extended into the respective casing members by 85 way of the openings, the casing members having removable plugs.

3. A universal joint comprising two forked members at approximately right angles to each other and the branches of which have external studs, a ring surrounding the forks 90 and in which the studs are pivotally received to connect the forked members for universal movement, a series of hollow segmental lubricant receiving casing members surrounding the ring and the ends of which are contiguous, the casing members having openings 95 and the studs having extensions extended into the respective casing members by way of the openings, the casing members having removable screw-threaded plugs opposite said extensions.

4. A universal joint comprising two forked members at approximately right angles to each other and the branches of which have external studs, a ring surrounding the forks 110 and in which the studs are pivotally received to connect the forked members for universal movement, a series of hollow segmental lubricant receiving casing members surrounding the ring and having inwardly extending tubes furnished at their inner ends with outwardly and inwardly extending flanges, bushings fitted around the studs and inclosed by the tubes, and having flanges at their inner ends, packings between the flanges of the 115 bushings and the outer flanges of the tubes.

5. A universal joint comprising two forked members at approximately right angles to each other and the branches of which have external studs, a ring surrounding the forks 125 and in which the studs are pivotally received to connect the forked members for universal movement, a series of hollow segmental lubricant receiving casing members surrounding the ring and having inwardly extending 130

tubes, bushings fitted around the studs and inclosed by the tubes, the tubes and the bushings having means therebetween for the conduct by centrifugal action of oil from the 5 inner ends of the bushings to the interiors of the segmental casings.

6. A universal joint comprising two forked members at approximately right angles to each other and the branches of which have 10 external studs, a ring surrounding the forks and in which the studs are pivotally received to connect the forked members for universal movement, a series of hollow segmental lubricant receiving casing members surround- 15 ing the ring and having inwardly extending

tubes, bushings fitted around the studs and inclosed by the tubes, the tubes and the bushings having means therebetween for the conduct by centrifugal action of oil from the inner ends of the bushings to the interior of 20 the segmental casings, the joint having means to positively prevent the lateral passage of oil from the tubes.

In testimony whereof I hereby affix my signature.

HARRY M. FUNNELL.
